4 Claims. (Cl. 94—51)

ABSTRACT OF THE DISCLOSURE

Vehicular apparatus for implanting joint devices in unset concrete in which there is a set of jaws for: gripping and compressing the resilient head of a joint device; holding it compressed while being concurrently vibrated and forced into the unset concrete and ejected from the jaws. The jaws and their actuating equipment are mounted for movement about a horizontal axis so that the jaws may face upwardly while being charged with the joint device, but face downwardly while implanting and ejecting it.

This invention relates generally to the application of expansible and contractible joint devices in concrete slabs, and particularly concerns an apparatus for facilitating the implanting of such joint devices in unset bodies of concrete, or the like.

Cracks resulting from expansion or contraction in concrete slabs have ever been a problem to the construction industry. The magnitude of the problem has been said to be geometrically proportional to the magnitude of the slab. In some cases, the best protection against multiple cracks in concrete is to induce such cracking at a few places, as by scoring the concrete when it is yet unset, or by sawing the cut slab at least part-way through after it has set. Such control of the locus of cracking, however, provides no protection against the likelihood of buckling due to expansion. In order to minimize the latter, it has heretofore been proposed to incorporate strips of more or less compressible material in the concrete slab as it is poured, so that, as the slab of concrete elongates under heat, the compressible strips will yield and accommodate the increasing dimension of the concrete. However, once such compressible material has been so compressed, it seldom resumes its initial less compressed condition, and consequently leaves a crack between it and the adjacent concrete in which moisture may accumulate and, under freezing conditions, damage the adjacent concrete.

More recently it has been proposed to provide a joint device having a body of highly resilient material, and an associated anchoring device which may be inserted in a poured slab of concrete before the concrete has set; and if inserted with the highly resilient material in a highly compressed state and then released from the compressing forces, the low degree of flowability of the concrete inhibits the resilient material from resuming its initial uncompressed dimension, and accordingly when the concrete sets, the joint device is but partially compressed so as to be free to expand when the concrete contracts, and free to contract when the concrete expands. The last-mentioned idea has met with success, but difficulties encountered in implanting such joint devices in concrete bodies of substantial dimension have militated against their use.

It is therefore an object of the present invention to provide a method and means for implanting joint devices of the character aforesaid in poured bodies of concrete without regard to their dimension within practical limits.

2

It is a further object of the invention to provide a method and means for facilitating and expediting such an implanting operation.

Generally stated, these and other objects of the invention are accomplished by the provision of a portable jaw bridge of such length as to extend from one side to the other of a poured concrete body, and equipping said jaw bridge with a pair of relatively movable jaws which are so thin, or otherwise configurated, that upon insertion into a body of concrete which is in the process of setting, they displace so little of the concrete that when the jaws are removed, the resilient member of the joint device may expand to occupy the space previously occupied by the jaws, but still remain under substantial compression. The invention further contemplates that the jaw bridge be mounted on a portable vehicle, truck, or frame in such manner that it is readily maneuverable and actuatable to:

- 10 (a) Receive and compress the resilient part of the joint device,
- 20 (b) Drive the joint device to the desired depth in the body of concrete while maintaining the resilient part of the device compressed, and

(c) Hold the joint device in its implanted position while the jaws are withdrawn from the body of concrete.

25 An illustrative embodiment of an apparatus for performing the aforesaid functions is shown in the accompanying drawings, in which:

30 FIGURE 1 is a perspective view of a joint device of a character which typifies those employed in accordance with the present invention;

35 FIGURE 2 is a fragmentary cross-sectional view showing the joint device of FIGURE 1 implanted in a body of concrete in accordance with the present invention;

40 FIGURE 3 is a perspective view of an implanting apparatus constructed in accordance with the present invention, with the jaw bridge thereof positioned to receive a joint device of the character shown in FIGURE 1;

45 FIGURE 4 is a view corresponding to FIGURE 3, but showing the apparatus loaded with a joint device and ready to be inserted in a slab of concrete which is in the process of setting;

50 FIGURE 5 is a view corresponding to FIGURE 4, but showing the apparatus in position where the joint device has been driven into the body of concrete;

55 FIGURE 6 is a sectional view taken along line 6—6 of FIGURE 5;

60 FIGURE 7 is a view corresponding to FIGURE 6, but showing the apparatus at the completion of its discharge of the joint device; and

65 FIGURE 8 is a view in side elevation of a portion of the jaw bridge from the side thereof seen in FIGURE 3, but not seen in FIGURES 4 and 5.

While the joint device shown in FIGURES 1 and 2 forms no part of the present invention, an understanding of it is essential to an understanding of the operation and results of the apparatus to be later described. Such a joint device consists essentially of one or a pair of metal strips 1, preferably as long as the width of the concrete slab into which it is to be implanted, having a flange 2 at the lower edge thereof, and embedded for at least about half of its height in a block 3 of resilient material such as polyurethane foam. If separate strips 1, each having a flange 2, are employed, the strips are preferably connected together so that the flanges 2 thereof together form an arrowhead configuration. When the strips 1 are formed together, however, there is a fold at one extremity thereof.

In order to implant such a joint device in a body of concrete which is in the process of setting, the resilient block 3 is compressed, preferably to a thickness less than the combined spread of flange 2, and, while so compressed, is inserted into the body of concrete 4, where it expands in situ to approximately the relationship shown in FIGURE 2.

The apparatus of the present invention is intended to accomplish such compression and insertion of the joint device with limited displacement of the poured, but unset, concrete; and to do so with precision, as well as with a minimum of effort.

In the embodiment shown in the drawings, the apparatus comprises a pair of jaws 5 and 6, which are preferably of a length such as to extend entirely across the width dimension of a slab of concrete, that is to say, from the form at one side to the form at the other side of such slab. The jaws 5 and 6 are preferably made with removable sections at their respective ends, so as to be able to conform the length of the jaws to the width of slabs which, in the case of highway slabs, may vary as much as two or three feet. The adaptation of the length of the jaws 5 and 6 to varying widths of concrete slab may be conveniently accomplished by providing a central jaw section of, say, ten feet in length, with removable sections at each end, and replaceable end sections of different lineal dimensions.

In order to minimize the volume of concrete displaced in the process of implanting the joint device, it is preferable to make the jaws 5 and 6 as thin as possible. In the embodiment shown in FIGURE 6, it will be observed that the thickness of the jaws 5 and 6 is such that when the block 3 is compressed for insertion, the flanges 2 of the joint device extend slightly beyond the outside surfaces of the jaws 5 and 6. As a practical example, the jaws 5 and 6 are constructed of steel plate having a thickness on the order of 0.125 inch.

In the embodiment shown, the lower margins of the jaws 5 and 6 are scalloped to provide projecting fingers 7 intervened by open spaces 8, whose zeniths each preferably lie in a plane below the plane of the lower edge of block 3 when the ends of fingers 7 are engaged with the flanges 2 of a joint device, as shown in FIGURE 6. Below the plane of the zeniths 9, it is preferable that the openings 8 occupy at least about half of the total side surface area which would otherwise be included within the jaw plates 5 and 6. In other words, below the plane of zeniths 9, the residual metal which constitutes fingers 7 is preferably no greater in area than that of the openings 8. This facilitates ingress of the flowable concrete through the openings 8, and behind fingers 7, into contact with strip 1 as the joint device is in the process of implantation, so that the strip 1 will be completely embedded in concrete up to the level of the lower end of block 3 before jaws 5 and 6 are released and withdrawn. The openings 8 are not necessarily of arcuate configuration, and, if desired, may be made polygonal.

Any suitable arrangement may be provided for moving the jaws 5 and 6 toward and away from each other, so as to grip and release, respectively, the joint device; to compress the block 3; and to impart a driving force to the joint device. In the form shown, the jaws 5 and 6 are mounted upon a jaw bridge consisting of a plate 10, provided along its upper edge with a series of eye bolts 11, and along its lower edge with a series of holes 12. Each eye bolt 11 serves the dual function of connecting angles 13 and 14 to the plate 10, and of accommodating hinge pin 15 for bracket 16. Pivots mounted in depending relationship from angle 14, there is a series of fluid actuated piston-cylinder organizations 17, to the lower end of which is pivotally connected a toggle linkage consisting of links 18 and 19, the former being hinged to plate 10 by a hinge pin 20, and the latter being hinged to bracket 16 by a hinge pin 21; and the two links 18 and 19 being hinged together and to the rod of piston-cylinder organization 17 by a hinge pin 22. Aligned with each of the

holes 12 is a cup 23, having an adjusting screw 24 held captive therein. Similarly, the lower end of each bracket 16 is provided with a cup 25 having an adjusting screw 26 held captive therein. The adjusting screws 24 and 26 are respectively provided with threaded pilots 27 and 28, which engage blocks 29 and 30 slidably received, respectively, within the cups 23 and 25, and, in case of the former, also received within holes 12. The block 29 is secured, as by welding, to jaw 6, and the block 30 is secured, as by welding, to the jaw 5. Thus, the adjusting screws 24 and 26, with their adjunct parts, provide for adjustment of jaws 5 and 6 relative to each other and relative to plate 10 on the one hand, and bracket 16 on the other hand; for adjusting the degree to which block 3 can be compressed; as well as providing for quick release and attachment of separable sections of the jaw plates. It will be understood that the plate 10 is appropriately apertured to permit the passage of links 19 therethrough between hinge pins 21 and 22.

In the condition shown in FIGURE 6, fluid pressure is being exerted within piston-cylinder organization 17 in order to draw hinge pin 22 upwardly, and cause jaws 5 and 6 to move toward each other, so as to grip and compress block 3 of the joint device. In the condition shown in FIGURE 7, however, the fluid pressure has been applied in piston-cylinder organization 17 so as to move hinge pin 22 downwardly from the position shown in FIGURE 6 in order to release the gripping force on block 3.

Any desired number of piston-cylinder organizations, such as 17, and their adjunct toggle linkages, as well as brackets 16, may be provided on the jaw bridge at appropriate spacing lengthwise thereof.

Between the jaws 5 and 6, there is mounted a stripper plate 31, which may be a plate of steel, or other rigid material, having a thickness on the order of about 0.125 inch, and extending for a distance at least as great as the length of jaws 5 and 6. The stripper plate 31 has a straight lower edge for setting against the top end of block 3 of the joint device. The stripper plate is also provided with apertures 32 to accommodate the passage of links 19, and permit vertical movement of the stripper plate relative to jaws 5 and 6, as well as the other parts of the jaw bridge. The apertures 32 provide for movement of the stripper plate between the joint device inserting position, shown in FIGURE 6, and the stripping position (during removal of jaws 5 and 6 from the concrete shown in FIGURE 7). Beyond the ends of the jaws 5 and 6, the stripper 31 is provided, at each end thereof, with a toe plate 33. The toe plates 33 are for the purpose of holding the stripper plate 31 in engagement with the top end of the block 3 while the jaws 5 and 6, as well as the balance of the jaw bridge, are moved upwardly from the position shown in FIGURE 6 to the position shown in FIGURE 7 after the joint device has been implanted. The stripper plate 31, when so held down by pressure on toe plates 33, thus assures that the joint device will not follow the jaws 5 and 6 in their upward movement during withdrawal.

The entire jaw bridge is preferably mounted upon a vehicle, or otherwise made readily portable. In the form shown in the drawings, the vehicle is equipped with flanged wheels 34 arranged to ride upon forms of the type conventionally employed in pouring concrete highway slabs, such as illustrated at 35. The wheels 34 are preferably mounted upon stub axles, which are longitudinally extensible and retractable in order to adapt them to varying distances between opposite forms, such as 35.

The vehicle is preferably equipped with a source of power such as an internal combustion engine, or an electric motor, arranged to drive a suitable source of fluid pressure 36, and provided with suitable controls, such as 37 and 38, for controlling the flow of pressure fluid to piston-cylinder organizations 17 and other fluid actuated devices later to be described. In addition, the vehicle shown in FIGURES 3, 4 and 5 includes a storage box 39, within which may be kept a working supply of joint devices, as

well as removable and replacement sections of jaws 5 and 6, together with such other tools and accessories as may be desirable.

The jaw bridge is mounted upon the vehicle through a pair of offset hinges 40, each connected at one end thereof to the angles 13 and 14, and at the other end through a hinge pin 41 to a clamp 42, which is secured to move with a cylinder 43 of a piston-cylinder combination whose piston rod 44 is fixedly connected to the carriage of the vehicle through a bracket 45. One such hinged, and one such piston-cylinder combination, are preferably provided near each end of the jaw bridge.

The hinges 40 provide for movement of the jaw bridge between the charging position shown in FIGURE 3 (where the jaws 5 and 6 are at the top side of the jaw bridge) and the operative or implanting position shown in FIGURES 4 and 5 (where the jaws 5 and 6 are on the lower side of the jaw bridge).

In the embodiment shown, the jaw bridge is moved between the position shown in FIGURE 3 and the position shown in FIGURE 4 by manual manipulation of the handle bars 46, one set of which is provided at each end of the jaw bridge, but it will be understood that when and if desired, such movement can be accomplished by power-driven equipment.

When in the position shown in FIGURE 3, with the pressure on piston-cylinder combinations 17 relaxed, a joint device may be readily inserted between the jaws 5 and 6, so that upon energization of piston-cylinder combination 17, the resilient block 3 of the joint device will be engaged and compressed by movement of the jaws toward each other. When sufficiently compressed for implanting in the concrete, the joint device moves with the jaw bridge about the hinges 40 until it assumes the position shown in FIGURE 4, and is then lowered by control of the fluid pressure within piston-cylinder combination 43 until the flanges 2 of the joint device are at, or near, contact with the surface of the poured but unset concrete slab. Upon reaching this position, the fluid pressure within piston-cylinder combination 43 may be released, so that the weight of the jaw bridge tends to drive the joint device, as well as the jaws 5 and 6, into the concrete slab. This driving action may be promoted by one, two, or all of three means: first, by downward pressure on the handle bars 46; second, by operation of a vibrator 47 midway of the length of the jaw bridge on flanges 13 and 14; third, by the admission of pressure fluid into piston-cylinder combination 43 in a direction such as to drive hinge 40 downwardly. The vibrator 47 is preferably fluid-pressure operated, and is provided with a driven rotor having an axis which extends substantially parallel with the lengthwise dimension of the jaw bridge, and whose center of gravity is eccentric with respect to the axis of rotation, so as to produce vibrations having an amplitude on the order of an eighth of an inch or less.

When the jaw bridge, with its engaged joint device, has moved downwardly for a distance sufficient to implant the joint device in the concrete at a depth such that the top of the compressed resilient block 3 is reasonably close to the surface of the concrete slab, as shown, for example, in FIGURE 6, the pressure in piston-cylinder combination 17 may be relaxed, but preferably not sufficient to actively force jaws 5 and 6 apart to a substantial degree. While the clamping action of the jaws is thus relaxed, attendants at opposite ends of the jaw bridge may each put a foot upon the toe plates 33, and then either lift the jaw bridge manually, or admit pressure fluid into cylinders 43 in a manner such as to cause them to lift the jaw bridge vertically. The relaxation of the grip between jaws 5 and 6, on the one hand, and resilient block 3, on the other hand, releases stripper 31 for vertical movement relative to the jaws 5 and 6, but the placing of each attendant's foot upon the toe plates 33 assures that the stripper plate 31 will not move upwardly as the jaws 5 and 6 move upwardly to resilient block 3 of the joint device.

Such relative movement of the stripper plate 31 relative to the jaws is limited by the expanse of apertures 32 in the stripper plate. While the projection of links 19 through such apertures can, if desired, be relied upon to so limit such relative movement, it is preferable to provide, in plate 10, a series of abutments 48, which are arranged to contact the upper edge of apertures 32 when the stripper plate has reached the downward extreme of its movement relative to jaws 5 and 6.

In the course of raising the jaw bridge as last described, while the stripper plate is held in position, as shown in FIGURE 7, where its lower edge rests upon the top of resilient block 3, the joint device is held in its implanted position by the dead weight of the stripper plate, plus, if need be, the resistance of implanted human feet upon the toe plates 33. Once the jaw bridge is elevated to the point where the extremities of fingers 7 in the jaws 5 and 6 are clear of the surface of the concrete, the jaw bridge may be rotated from the position shown in FIGURE 4 to the position shown in FIGURE 3, where it is ready to receive another joint device, and proceed with the implantation thereof at an appropriate distance from the locus of its last operation.

From the foregoing description, those skilled in the art should understand that the invention accomplishes its objects, and provides a convenient, economical and easily operated mode of implanting joint devices of the character described in slabs of concrete which is in the process of setting, all without unduly disturbing the concrete, or inhibiting its flow into anchorage about the flanges 2 of the joint device. If the concrete is in a condition of relatively high flowability when the jaws 5 and 6 are withdrawn from it, the convergence of the concrete upon opposite sides of the compressed block 3 through openings 8, while the block is still held compressed by fingers 7, tends to prevent expansion of the portions of the block engaged by fingers 7 from substantial recovery of their naturally expanded state as the fingers are drawn past them. When the resilient block 3 is made of slow recovery polyurethane material, the rate of convergence of the concrete, even in a relatively low state of flowability, is nonetheless sufficiently rapid to arrest expansion of block 3 before it has recovered substantially from its fully compressed state. Thus, the ultimate result is not only to provide a secure anchorage of the joint member by the convergence of flowable concrete about it before relaxation of the grip of jaws 5 and 6, as well as afterwards, but also to obtain a substantially watertight joint between the compressed head 3 of the joint device and the contiguous bodies of concrete.

While one complete embodiment of the invention has been disclosed in detail, such disclosure is merely illustrative of the invention, and not intended as a limitation upon it. Those skilled in the art will readily perceive of modifications and variations which fall within the spirit of the invention, and such are intended to be within the spirit of the appended claims.

Having thus described the invention, what is claimed and desired to be secured by Letters Patent is:

1. Apparatus for implanting joint devices having resilient heads and depending anchors in a slab of unset concrete, comprising a vehicle of length sufficient to bridge the width of said slab, a jaw bridge extending lengthwise of said vehicle, a hinge connecting said jaw bridge to said vehicle, said hinge having an axis extending lengthwise of said vehicle, means mounting said hinge axis for vertical movement relative to one of

(a) said vehicle, and

(b) said jaw bridge,

said jaw bridge having a pair of relatively movable opposite jaws, means mounting said jaws on said jaw bridge for movement toward each other to grip and compress the resilient head of a joint device and for movement away from each other to release said resilient head, and means for vibrating said jaw bridge.

2. The combination of claim 1 having a plurality of fluid-pressure responsive means for driving said jaws into and out of compressing relationship with said resilient head.

3. The combination of claim 1 having a stripper plate 5 between said jaws, and means for moving said jaw bridge vertically relative to said stripper.

4. The combination of claim 1 wherein said jaws have a plurality of spaced fingers for engaging said joint device below said resilient head, and the space between adjacent 10 ones of said fingers is at least as great as the area of a finger.
